UNITED STATES PATENT OFFICE

135,481

DESIGN FOR AN ELECTRON DISCHARGE TRANSMITTING TUBE

Winfield G. Wagener, Palo Alto, and Clark H. Sphar, San Francisco, Calif., assignors to Heintz & Kaufman, Ltd., South San Francisco, Calif., a corporation of Nevada

Application December 23, 1941, Serial No. 104,793

Term of patent 14 years

To all whom it may concern:

Be it known that we, Winfield G. Wagener and Clark H. Sphar, citizens of the United States of America and residents of Palo Alto, county of Santa Clara, State of California, and the city and county of San Francisco, State of California, respectively, have invented a new, original, and ornamental Design for an Electron Discharge Transmitting Tube, of which the following is a specification, reference being had to the accompany drawing, forming part thereof.

The figure is a perspective view of an electron discharge transmitting tube, showing our new design.

We claim:

The ornamental design for an electron discharge transmitting tube, substantially as shown.

WINFIELD G. WAGENER.
CLARK H. SPHAR.
